ANTISLAP PISTON

Application filed December 14, 1931. Serial No. 581,010.

The invention relates to pistons of that type adapted to be held against one wall of the cylinder by resilient pressure sufficient to prevent or minimize piston slap and forms in part a continuation of my earlier filed application, Serial No. 533,269. More specifically, the invention has reference to pistons in which a spring pressed shoe is placed in a recess in the skirt of the piston so as to bear against one wall of the cylinder and to press the body of the piston against the opposite wall thereof. One difficulty encountered with this latter construction is the tendency for the shoe to move axially with respect to the recessed body due to frictional retarding of its movement along the cylinder wall. This will cause a reciprocation of the shoe in its recess during each reciprocation of the piston which in time will wear the parts and produce a slap of a different character. Thus the main object of the construction will be defeated.

It is the object of the present invention to obtain a construction in which slapping of the shoe in its recess is effectually prevented. It is a further object to obtain an improved construction which is more effective in preventing slap and at the same time is one which can be manufactured at low cost. With these objects in view the invention consists in the construction as hereinafter set forth.

In the drawings:

Figure 1 is a side elevation of the piston showing the same within the cylinder; Figure 2 is an elevation partly in section viewed at right angles to Figure 1; Figure 3 is a horizontal section substantially in the plane of the axis of the wrist pin; Figures 4 and 5 are a plan view and side elevation respectively of the resilient expander; Figures 6 and 7 are views similar to Figure 2 showing modified constructions; Figure 8 is a section similar to Figure 3 showing another modification; Figures 9 and 10 are views similar to Figures 1 and 2 showing still another modification.

Piston slap is due primarily to rod angularity which where the piston loosely fits the cylinder will thrust it alternately against

the opposite walls thereof in the plane of movement of the rod. It has been found that this slapping movement can be best counteracted by resiliently holding the piston against one wall of the cylinder in a plane transverse to the plane of angular movement of the rod, as this reduces the amount of pressure required. Thus various constructions have been designed for pressing the body of the piston in the direction of the wrist pin axis. The present construction is of this general character and comprises a shoe which surrounds the wrist pin and is in engagement with a correspondingly shaped recess in the piston body. In detail, A is the piston head, B the skirt, C the bosses or bearings projecting inward from the skirt for holding the wrist pin D. Surrounding the wrist pin and one of the bearings C therefor is an annular recess E for receiving a correspondingly shaped shoe F. This recess may be either concentric or eccentric with respect to the axis of the wrist pin and may also be of any desired contour such as round, oval, square, etc. As shown in Figure 2 the recess E is circular in form and concentric with the axis of the wrist pin, the shoe F being of similar form. In Figure 6 the recess is of oval form and eccentric to the axis of the pin and in Figure 7 it is substantially rectangular in form.

The shoe F engaging the recess E must have sufficient clearance therein for free movement, this being necessitated by the fact that cylinders of internal combustion engines when in operation are expanded by the heat of combustion at their upper ends so as to impart thereto a slight tapering form. Consequently in each reciprocation of the engine the shoe must move inward and outward in its recess to compensate for the difference in diameter of the cylinder at its upper and lower ends. Where sufficient clearance is provided to insure this freedom of movement of the shoe in its recess there will also be freedom for movement of the shoe in the direction of the axis of the piston, this being occasioned by drag on the shoe due to friction with the cylinder wall which as before stated causes

a slap of the shoe alternately against the upper and lower walls of the recess.

To avoid the difficulty just referred to I have provided means for holding the shoe from movement in its recess axially of the piston while permitting freedom of movement radially thereof. This may be accomplished in several ways as follows: As shown in Figure 3 the shoe F has arranged there-beneath within the recess E a corrugated resilient ring G which supplies the desired radial pressure. The points of contact between the corrugations of this ring and the shoe and also between the ring and the bottom of the recess are relatively limited in area. On the other hand, the external surface of the shoe which bears against the cylinder wall presents a contact area of much greater extent and consequently the contact pressure against these limited areas is much higher than the pressure against any equal area of the outer face of the shoe. I have discovered that this difference of pressure will produce an excess of friction between the shoe and the bottom of the recess over the friction between the shoe and the cylinder wall. While I am aware of the general law that friction is independent of the area of contact, nevertheless with these limited contact areas there appears to be a higher coefficient of friction, doubtless due to the breaking through the lubricant film. Whatever the cause, the practical effect is that the shoe is held against objectional slap in its recess in an axial direction, even where clearance in said recess is considerable.

The fact that the shoe need not closely fit the walls of the recess may be utilized in reducing cost of manufacture. Thus instead of requiring accurate machining of the parts both the shoe and the recess in the piston skirt may be formed by die casting. This also permits of making these of different contours than would be possible if the surfaces required machining. Thus as shown in Figure 6 the shoe F is of an oval annular form and is arranged within a correspondingly formed recess E. In Figure 7 the shoe F² is of a substantially rectangular form engaging a corresponding recess E². In each case the shape of the corrugated ring is of a similar contour.

The resistance to movement of the corrugated ring G at the points of contact may be partially due to the imbedding of the same in the contacting surface. It is therefore desirable to provide a sufficient number of corrugations so as to insure the radial arrangement of the same at points in the circle less than 180 degrees. Preferably I form eight corrugations, four projecting in one direction and four in the reverse direction. This will insure that at least two of the corrugations on each side will be ar-

ranged transverse to the axial movement of the piston and will therefore hold the shoe from slap in this direction.

Pistons are frequently made of aluminum and other light metals to reduce the inertial forces in high speed operation. As these metals are relatively soft it is desirable in some instances to provide surfaces of harder material. For instance, if both the piston and the shoe are formed of soft aluminum the corrugated resilient ring G might in time wear too deeply into the contacting surfaces. This effect may be avoided by the construction shown in Figure 8 in which H is a pressed steel cup fitted within the recess E³ and having a bottom portion H' against which the corrugations of the ring G bear. The shoe F³ is provided with another pressed steel cup I which is of a size to loosely fit within the cup H and which provides a bottom surface I' for contact with the corrugations of the resilient ring G.

Another modification of my invention is shown in Figure 9 in which the shoe is held by other means than friction against axial slap. Thus as shown the shoe F³ is attached to a steel strip J which is anchored at its end K to the piston skirt. A portion of this strip J is corrugated at L to bear against the bottom of the recess so that the shoe is resiliently pressed outward against the cylinder wall. At the same time the portion of the strip J between the anchoring point K and the shoe forms a link which positively holds the shoe from any movement relative to the skirt in the direction axially of the piston. With all of these various modifications the same essential functions are performed viz, the free radial movement of the shoe in its recess and the prevention of any movement in a direction axially of the piston which would result in objectionable slap.

What I claim as my invention is:

1. The combination with a piston provided with a skirt portion having a recess therein, of a shoe in said recess having sufficient clearance therein for free movement in a radial direction, and resilient means for moving said shoe radially outward having an associated instrumentality for preventing slapping of said shoe in its recess in a direction axially of said piston.

2. The combination with a piston provided with a skirt having a recess therein, of a shoe in said recess having sufficient clearance therein to permit of free radial movement and a corrugated resilient member in said recess for pressing said shoe in a radial direction and for also holding said shoe from slap in said recess in a direction axially of the piston.

3. The combination with a piston provided with a skirt having a recess therein surrounding the wrist pin, of a shoe in said

recess having sufficient clearance therein to permit of free radial movement and to compensate for expansion or contraction, and an annular corrugated resilient member corresponding in shape to the outer periphery of said shoe arranged within said recess and having bearings of limited area respectively upon the bottom of said recess and upon said shoe whereby the latter is pressed radially outward and is held from slap in said recess in a direction axially of the piston.

4. The combination with a piston provided with a skirt having a recess therein surrounding the wrist pin, of a shoe in said recess having sufficient clearance therein to permit a free radial movement and an annular corrugated resilient member corresponding in shape to the outer periphery of said shoe and arranged in said recess, the corrugations of said member forming bearings of restricted width on said shoe and on the bottom of the recess extending in a radial direction to hold said shoe from slap in said recess.

5. The combination with a piston provided with a skirt portion having a recess therein surrounding the wrist pin, of a shoe in said recess having sufficient clearance therein for free movement in a radial direction, at least one of said members being formed of relatively soft metal, a corrugated resilient member formed of harder metal arranged in said recess to press said shoe in a radial direction and for also holding said shoe from slap in said recess in a direction axially of the piston and a lining of harder metal adjacent to the member formed of softer metal for limiting wear by said corrugated member.

6. The combination with a piston provided with a skirt having a recess therein surrounding the wrist pin and a shoe in said recess having sufficient clearance therein to permit of free radial movement, said piston skirt and shoe being formed of relatively soft metal, a corrugated resilient member in said recess for pressing said shoe in a radial direction and for also holding said shoe from slap in said recess in a direction axially of the piston, and linings of harder metal for said shoe and the bottom of said recess to limit wear by the corrugations of said resilient member.

7. The combination with a piston provided with a skirt portion having a recess therein, of a shoe in said recess having sufficient clearance therein for free movement in a radial direction, said piston and shoe being formed of relatively soft metal, a corrugated resilient member in said recess for pressing said shoe in a radial direction and for also holding said shoe from slap in said recess, and cups of harder metal arranged in said recess and upon said shoe for

limiting the wear by the corrugations of said resilient metal.

8. The combination with a piston provided with a wrist pin, of an annular shoe engaging the cylinder wall surrounding said wrist pin and resilient means reacting on said shoe and piston to hold the latter against one wall of the cylinder.

9. The combination with a piston, a wrist pin and bosses projecting inwardly from the opposite sides of the piston forming bearings for said pin, of an annular recess in one of said bosses surrounding the axis of the wrist pin, an annular shoe engaging said recess and having its outer face fashioned to conform to the cylinder wall and resilient means within said recess reacting on said shoe and piston to hold the latter against one side of the cylinder wall.

10. The combination with a piston and a skirt thereof, of a wrist pin, bosses extending inward from opposite sides of the piston skirt forming bearings for said wrist pin, one of said bosses being enlarged in diameter and provided with an annular recess therein surrounding the axis of the wrist pin, an annular shoe engaging said recess having its outer face conforming to the cylinder wall and resilient means within said recess reacting on said shoe and piston to hold the latter against one side of the cylinder wall.

11. The combination with a piston and wrist pin, of a boss projecting inwardly from the piston forming a bearing for said wrist pin and provided with an annular recess concentric with the axis of the pin, an annular shoe engaging said recess and externally conforming to the cylinder wall, and a warped resilient ring within the recess in rear of said shoe for reacting thereagainst and forcing said piston against one wall of the cylinder.

In testimony whereof I affix my signature.

NORMAN T. HARRINGTON.
